Attorney

UNITED STATES PATENT OFFICE

GEORGE MILTON TOMLINSON, OF PHILADELPHIA, PENNSYLVANIA

ELECTROSURGICAL INSTRUMENT

Application filed June 20, 1929. Serial No. 372,370.

My invention relates to a surgical instrument.

A purpose of my invention is to mechanically guide an electro-surgical knife or wire. Where a clamp is used it may be made in one instrument with the knife or wire.

A further purpose is to combine a clamp and means for applying high frequency current to tissue compressed in the clamp, using the clamp to temporarily stop the flow of blood or lymph in the tissue and the high frequency current applied to the tissue during its compression to permanently seal the compressed passages in the tissue, thereby insuring that there will be no bleeding or lymphatic discharge after the clamp has been released.

A further purpose is to provide an instrument well adapted to safely remove the tonsil of a child, or any tonsil which is hypertrophied and exposed, combining means for clamping the tonsil at its basal support, with an electro-surgical knife for simultaneously severing the tonsil and effecting a sealing reaction upon the severed passages for blood and lymph.

A further purpose is to provide a spring retracted hemostat clamp with ratchet adjustment mechanism and a spring release for the ratchet, adapting the clamp to remain in any set position and to be quickly opened upon touching the spring release.

A further purpose is to avoid the need for crushing the basal attachment of a tonsil in order to prevent bleeding after a tonsil removal and to lessen the requisite operating voltage for a high frequency current of an electro-surgical knife by combining a clamp and electro-surgical knife.

A further purpose is to mount an electro-surgical member for applying high frequency current upon the front of a clamp member so as to adapt the instrument to clamp tissue to definite position and then to turn on the high frequency current and to push the clamp and applying member through the tissue.

Further purposes will appear in the specification and in the claim.

I have elected to show my invention applied to a tonsillotome in that it has proved

to be particularly advantageous in its application to this type of instrument and to show the broader features of my invention diagrammatically, selecting embodiments of my invention that are practical and efficient in operation and that well illustrate the principles involved.

Figure 1 is a side elevation of an instrument embodying a desirable form of my invention and having a particular application for removing tonsils.

Figure 2 is a top plan view of Figure 1.

Figure 3 is a diagrammatic detail section illustrating a different form in which the member for applying the high frequency current is mounted on the front of the clamp member for use first as a positioning clamp and then for removal of the positioned tissue.

Figure 4 is a diagrammatic view illustrating my combination of clamp and electro-surgical knife position to remove a hemorrhoid or the like.

Figure 5 is a view of a slightly different application of the structure shown in Figure 4.

Figure 6 is a detail diagrammatic elevation illustrating a combination between a clamp and a spring closure carrying a scale adapted to show the pressure exerted by the clamp.

Figure 7 is a view generally similar to Figure 4 but showing an electro-surgical knife operating upon tissue inwardly from a clamp, the clamped tissue being cut off while clamped, the return circuit taking place through the tissue being cut away.

Like numerals refer to like parts.

Describing in illustration and not in limitation and referring to the drawing:

The tonsillotome shown in Figures 1 to 3 combines a guillotine type of clamp and electro-surgical knife for easy and safe removal of tonsils.

A fenestra or guillotine frame 10 adapted to surround a tonsil 11 comprises the outer end of a frame guideway structure 12.

The fenestra slidably supports a clamp 13 in side grooves 14 and an electro-surgical knife 15 in side grooves 16 and the frame 100

structure 12 carrying the fenestra is supported upon the body portion 17 of a hand grasping member 18.

The rearwardly extending frame 12 comprises a housing and guiding support for the shank portions 19 and 20 of the clamp and of the electro-surgical knife respectively.

The flat shanks 19 and 20 are provided with guides 21 and 22 respectively toward

10 the front and rear of the frame structure and are vertically slotted at 23 and 24 to pass an operating finger 25 which is pivoted at 26 to the member 17 and is preferably integral with a movable handle 27.

15 The frame structure 12 is rigidly fastened to the top of the hand grasping member 18 as by a pin 28 extending downward from the frame structure into a suitable hole in the top of the hand grasping member, a thumb

20 screw 29 normally engaging the pin to hold the framework normally rigid with respect to the handgrasping member.

25 The pivoted handle 27 presents the operating finger 25 through the slots 23 and 24 of the clamp and electro-surgical knife.

The slot 23 through the flat rearward shank of the clamp loosely fits the opposite sides of the finger 25, so that the position of the clamp in the fenestra is determined 30 fairly closely by the angular position of the handle 27 while the slot 24 through the shank of the electro-surgical knife is considerably longer than the width of the operating finger 25 in order to permit the knife member to be 35 moved forward after the clamp has been set in its clamping position.

40 I provide the shank of the electro-surgical knife with a rearwardly extending rod 30 which passes through the guide 22 of the frame structure and carries a concaved flange thumb engagement member 31 at its rearward end.

45 The member 31 receives the operator's thumb when the electro-surgical knife is to be pushed forwardly to sever the clamped tonsil, and the knife is spring-retracted by a suitable spring 32 surrounding the rod 30 and compressed between the structure 12 and the push flange 31.

50 I provide a sector ratchet connection between the hand grasping members 18 and 27 showing the movable member 27 with a sector 33 adapted to slide in a suitable articulate opening 34 in the body 17 of the member 18.

55 The sector has ratchet teeth 34' along its inner side which are engaged by a cooperating pawl member 35 spring pressed at 36 to its engagement position at which it holds the sector from retraction.

60 The pawl member 35 is slidably mounted in a guiding recess 37 in the member 17 being spring pressed into engagement with the ratchet by the spring 36 and carries a U mem-

ber 38 for releasing the pawl from the teeth of the ratchet.

The release member 38 is rigidly fastened to the pawl and is suitably placed for easy engagement by the surgeon's thumb to effect release of the ratchet and a spring opening of the clamp.

The electro-surgical knife may desirably comprise a thin strip 40 of suitable metal or wire, as copper or silver, inserted between sheets 41 and 41' of insulation material. The fenestra is also insulated as at 42.

The knife has electrical connection at 43 to a conductor which in practice is connected at its other end to a source of high frequency 20 current adapted to electro-surgical use.

The other terminal of the high frequency current, where a second terminal is used, is usually connected to a plate that is placed in close contact or in contact with tissue being removed, as a loop or forceps or other means of contact. This is ordinarily a plate applied to the back of the patient. Other connections are shown diagrammatically in Figures 4 to 6 for local return where this is desired.

25 In operation the open fenestra is pushed down over the tonsils. In the case of a child the fenestra will pass through any adhesions, which in a child's tonsil are soft.

30 When the fenestra is at the bottom of the tonsil the clamp is gradually tightened, which lifts the tonsil out of its seat between the pillars of the palate, exposing it in position for the cut.

35 The clamp is then tightened preferably merely enough to stop any circulation in the clamped tissue of lymph or blood.

40 The surgeon then moves the electro-surgical knife slowly inward severing the tonsil, desirably moving the knife several times back 105 and forth over the cut to insure perfect sealing of the severed passages.

45 My method has a great advantage over the practice hitherto of having to crush the tissue in the clamp in order to prevent bleeding after 110 the cut.

50 After a surgeon has closed the clamp it is held in its set position by the ratchet member.

55 During closure the operator should judge by feel as to the tightness of clamping and the ratchet makes it unnecessary for his attention to be directed to maintaining the clamp at the proper tightness while making the cut.

60 If the cut is made fairly rapidly and the knife is operating at a relatively low voltage I prefer to move the knife back and forth slowly over the severed tissue in order to insure complete coagulation of the blood and lymph compressed in the tissue, this coagulation sealing the severed passages so perfectly that there is no danger of bleeding after the clamp has been loosened.

65 The operation is considerably more rapid 135

and more safe than has been possible in the past.

I avoid the need for the intense crushing of the tissue at the base of the tonsil which has hitherto been usual preparatory to making the cut, and continued for about two minutes thereafter in order to secure a merely fair degree of safety from subsequent bleeding after the clamp is finally released.

Even with this relatively intense crushing pressure there has been no certainty that bleeding will not start after the clamp is removed, either at once upon loosening the clamp or perhaps after a considerable period.

I avoid to a great degree the possibility of secondary infection incident to bacterial invasion through open lymphatic and vascular channels and to partial devitalization through intensive clamping of the parts.

I am also enabled to operate my electro-surgical knife more rapidly or with lower voltages, either or both, as compared with the electro-surgical knives of the prior art in view of operation upon tissue under compression, the compressed passages of the tissue containing greatly reduced quantities of blood and lymph that is stationary and very easily coagulated by the high frequency current at lower voltages than has been necessary in the past.

I use a clamp to exactly position the tissue that is to be severed and preferably tighten the clamp, merely enough to hold the tissue in the desired position and to stop any circulation of lymph or blood in the tissue during the cutting, and cut by mechanically guiding the electro-surgical knife through the compressed tissue. If desired the tissue can be crushed by the clamp, as in prior practice, using the electrical coagulation for the purpose of ensuring the freedom from bleeding which was sought but not reliably secured by the crushing.

I have in Figures 1 to 3 shown my invention embodied upon a tonsillotome in that it is particularly advantageous for this use; its broader features however apply to any combination between a clamp and means for applying high frequency current to tissue held in the clamp with a sealing of the tissue passages at the point of current application and with or without cutting of the tissue.

In Figure 4 the clamp 13¹ is shown applied to the normal tissues annexed to any growth 11¹ to be removed.

The surgical knife 15¹ is shown in position to sever the growth at the same time preventing danger of bleeding after the clamp has been removed.

The conducting element 40¹ of the knife is embedded in insulation material 41¹ and is electrically connected at 44 to any suitable source of high frequency current.

The other terminal 45 of the source of current is connected to the conducting body 13¹

of the clamp and also desirably to a contact plate 46 in intimate contact with the body of the patient at any suitable place.

Preferably there should be sufficient reactance in the circuit to avoid any danger of burning the tissue except at the edge of the knife, the current being limited by this reactance to a value so small as to make the contact between the clamp and compressed tissue sufficient to insure a safe and ample return through the clamp.

The reactance may be either in the portion of the circuit beyond the terminals 44 and 45 not shown or may be inserted by the operator as 47, Figures 5 and 6.

An advantage in making the return through the clamp is the localizing of the current to the affected part.

As before the simultaneous cutting and sealing of the tissue passages is accomplished by slowly moving the knife through the tissue, preferably moving the knife back and forth over the cut tissues if the applied voltage be so low as to make this desirable.

I may use the apparatus as a hemostat without cutting, for example as in Figure 5 where the tissue 11² projecting from the clamp 13² may have been cut with a non-electric knife and the clamp may have been applied in order to stop bleeding.

The clamp may then be tightened merely enough to stop bleeding by compressing the severed passages of the tissue and the high frequency current may be applied as before by a member 15², which is shown directed 100 perpendicularly inwardly in Figure 5 instead of across the tissue as in Figure 4.

In Figure 5 I show the reactance 47 to insure that there shall be no danger from short circuiting the contacts or from making the return circuit wholly through the clamp.

In Figure 6, I show a clamp 13³ spring pressed toward closure, the tension of the clamp being shown by the position of a scale 48 adjustably mounted upon a tie member 49 across the clamp arms 50 and 51. This is for the purpose of enabling the operator to adjust the pressure nicely to the needs and to avoid crushing the tissue.

The clamp arms are pivoted together at 52 and the tie member 49 has ends loosely passing through perforations in the arms.

The thumb nut 54 is used to tighten the clamp, the measure of tightness being shown by the position of the scale 48 with respect to the inner side of the arm 50 of the clamp.

I show the means for applying high frequency current as a wire member 55 carried in an insulating glass tube 56.

In the form shown in Figures 1 to 6 the cut is made on the tissue outside the clamp, the current flowing into the remaining tissue and returning either through the body of the clamp by reason of the contact that the clamp

body makes around the affected part or to any suitable contact plate, either or both.

In Figure 7 I show that the return may take place through the tissue that is being cut away and that the cut may be made upon the inner side of the clamp, an electro-surgical knife or needle 15⁴ being applied to the tissue back of the clamp 13⁴ and the return circuit taking place from the portion of the tissue 11⁴ that is being cut away to the clamp.

Though I prefer to provide a definite return for the circuit either to an electrode or the clamp, I recognize that this is not always necessary, particularly where the cutting or coagulating area is small, doubtless because the human body acts as a condenser avoiding the necessity for a current return as such or because of an adequate grounding of one terminal of the source and of the body operated upon.

For this reason in my claim I cover the condition in which a clamp may be used for the purpose of constricting and holding the tissue so that the cutting and coagulation may be effected to the best advantage but in which the clamp not only need not be a return electrode but in which no return electrode as such is used.

As shown in Figure 3 I may make the clamp 13 and knife 15 a single member adapted to initially clamp in order to definitely position the tonsil or other growth with which it is being used for cutting and then after the part has been properly positioned to apply the high frequency current and to sever the tissue by closing movement of the clamp.

In this figure the metallic knife blade 15 is covered at the sides with insulation material 41 which slides in the groove 14 of the fenestra.

The fenestra as before may be metal and the closure of the clamp initially takes place while the high frequency current is shut off. The metal should be insulated in some way.

The operator closes the clamp until the part that is to be severed is seen to be definitely in the desired position for severing. The current is then applied and the clamp gradually closed simultaneously cutting through the tissue and sealing the compressed passages by coagulating the lymph and blood.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

A surgical instrument including a clamp for holding and compressing tissue, a handle

supporting the instrument and including relatively pivoted members adapted to close upon one another by compression of the hand to close the clamp, and a ratchet adapted to hold the clamp in any closed position in combination with an electro-surgical knife adapted to be moved to tissue held in the clamp, a spring pressing the knife away from the clamp and a thumb engagement member to be engaged by the thumb and fastened to the knife adapted to be pressed by the thumb to bring the knife to the tissue.
